M. GILMORE

DOOR OPERATING MECHANISM

Filed May 16, 1921

UNITED STATES PATENT OFFICE.

MILLARD GILMORE, OF OAK PARK, ILLINOIS.

DOOR-OPERATING MECHANISM.

Application filed May 16, 1921. Serial No. 470,153.

To all whom it may concern:

Be it known that I, MILLARD GILMORE, a citizen of the United States, residing at Oak Park, in the county of Cook and State 5 of Illinois, have invented a new and useful Improvement in Door-Operating Mechanism, of which the following is a specification.

My invention relates to an improvement 10 in means for operating elevator and other doors from a distance, whether said doors move vertically or horizontally and whether a single door or a plurality of door sections are used in closing the door opening. More 15 specifically my invention consists in means for doing the above electrically and particularly in providing one or more electric solenoids for each door or door section cooperating with a suitable plunger or plungers and 20 connections extending from the plunger or plungers to the door or door sections and suitable electric circuits extending from the windings of the solenoid or solenoids to switching mechanism located at the desired 25 point of control and connected with a suitable source of electric current.

My invention will best be understood by reference to the accompanying drawings showing a preferred embodiment thereof, in 30 which

Fig. 1 illustrates my invention as applied to two vertically movable door sections used to close a single elevator opening,

Fig. 2 shows the parts of Fig. 1 in their 35 position assumed to open the elevator opening, and

Fig. 3 shows in a diagrammatic view, my invention as applied to a horizontally movable elevator door.

Similar numerals refer to similar parts 40 throughout the several views.

As shown in Fig. 1, my construction consists of upper and lower door sections 10 and 11 employed to close an opening 12 through a wall to an elevator. Suitable 45 vertical guides not shown, may be employed to maintain said door sections in the same vertical plane as they are moved to or from their open position shown in Fig. 2.

The section 10 has projecting from its 50 lower portion, brackets 13, 14 to which cables 15, 16 are secured, which cables extend upwards and around sheaves 17, 18 having fixed supports and then downwards 55 to engage the upper ends of the plungers 19,

20 of the solenoids 21, 22. The lower ends of the plungers 19, 20 have connected with them the cables or rods 23, 24 extending through the solenoids 25, 26 and secured to the brackets 27, 28 projecting from the lower 60 portion of the door section 11. It will be seen that the construction described forms a counterbalanced system and for ease of operation it is desirable that the door sections shall be of substantially the same 65 weight. Where this is not the case suitable counterweights may be connected to the lighter door section, as for example, where the section 10 is heavier than the section 11, counterweights 29 may be connected to the section 11. In some cases it may be desired to use but a single door section as for example the section 10 to close the elevator opening and in this case all that is necessary is to make the counterweights 29 together of 70 substantially the weight of the section 10. 75

The plungers 19 and 20 are of magnetic material such as soft iron or steel and they and the windings of the solenoids are so proportioned that energization of the solenoids 21 and 22 moves said plungers and therefore the door sections to the position shown in Fig. 1 to close the opening 12 and energization of the solenoids 25 and 26 moves the 80 plungers and door sections to the position 85 shown in Fig. 2 to open the opening 12.

The circuit connections for operating the solenoids are as follows:

Main feed wire 30, from any suitable 90 source of electric current not shown is connected with contacts 32 and 33 of control switches S and S¹ respectively for closing and opening the door sections, and one terminal of each of the control solenoids 34 and 35. The other terminals of the solenoids 34 and 35 are connected by wires 36 and 37 with the push buttons or operating 95 switches 38 and 39. A second main feed wire 31 is connected with the contacts of the switches 38 and 39. The contacts 40 and 41 of switches S and S¹ are connected by wires 42 and 43 with the upper terminals of the solenoids 21 and 22 and the lower terminals of the solenoids 25 and 26 respectively. 100

The adjacent terminals of the solenoids 22 and 26 are connected together and by wire 44 with feed wire 31. The adjacent 105 terminals of solenoids 21 and 25 are connected together and by wire 45 with wire 44. The switches S S¹ are provided with 110

switch bars 46 and 47 for connecting the contacts 32, 40 and 33, 41 respectively by operation of the cores 48 and 49 connected respectively with said switch bars upon 5 energization of the corresponding solenoids 34 and 35. The cores 48 and 49 are connected by a lever 50 of insulating material, pivotally supported at 51 to insure that both of the control switches cannot be closed at 10 the same time.

It will be observed that the current required to operate the solenoids 34, 35 is small relatively to the current required to operate the solenoids 21, 22, 25 and 26 on 15 account of the small amount of work required to be done by the solenoids 34, 35. This permits locating the control switches S, S¹ near the elevator doors as is desirable to reduce power loss in the wiring, and at 20 the same time the switches 38 and 39 may be located at any remote point desired without material loss of power.

From the circuit connections described it will appear that operation of the switch 38 25 energizes solenoid 34 and operation of switch 39 energizes solenoid 35. Upward movement of contact bar 46 connects contacts 32 and 40 thus connecting the upper terminals of solenoids 21 and 22 through wire 42 with 30 feed wire 30 and energizing said solenoids. Upward movement of contact bar 47 connects contacts 33 and 41 thus connecting the lower terminals of solenoids 25 and 26 through wire 43 with feed wire 30 and 35 energizing said solenoids.

As a result, operation of the switch 38 energizes solenoids 21 and 22 and moves 40 plungers 19 and 20 to their upper position, closing the door sections 10 and 11 and operation of the switch 39 energizes the solenoids 25 and 26 and moves the plungers 19 and 20 to their lower position, opening the door sections 10 and 11.

In the construction shown in Fig. 3, a 45 single door section 10^a is used and has secured to its upper portion wheels 52 resting on a track 53 to support said door section for movement horizontally to open and close an elevator or other opening 54. Cables 55 and 56 extend from the upper portion of the door section 10^a in opposite directions horizontally and around guide sheaves 57 and 58 downwards and are connected with the plungers 20^a and 19^a of the solenoids 22^a and 55 25^a respectively for closing and opening the door section 10^a.

By providing the solenoids 22^a and 25^a with circuit connections and operating devices the same as described above for the solenoids 22 and 25, the door section 10^a may be operated in the same manner described above for the construction shown in Figs. 1 and 2 and with the same advantages.

It will be observed that if desired the solenoid mechanism may be directly connected

to the doors to be operated, for example with the construction shown in Fig. 3, the solenoids may be placed in horizontal position and the plungers may be connected directly with the door 10^a and that the operation of 70 the system will be substantially as described above.

It will be observed that swinging doors may be opened and closed by the use of substantially the same means described above, 75 for example using the operating devices shown in Fig. 3, the cables 55 and 56 may be connected with the door or with a bracket carried by the door at a point sufficiently removed from the hinged edge of the door 80 so that the operation of one of the solenoids 22^a and 25^a, for example the solenoid 25^a will open the door and the operation of the other of said solenoids, for example the solenoid 22^a, will close the door. 85

Again, it will be apparent that shutter doors of the type that roll up on cylinders to open the doorways, may be opened and closed by the use of substantially the same means described above, for example, using 90 the operating devices shown in Fig. 3, the cables 55 and 56 may be connected together and either of the sheaves 57 and 58 may be rigidly secured to the shaft or end stud carrying the cylinder for receiving the shutter door, for which arrangement operation of one of the solenoids 22^a and 25^a, for example the solenoid 25^a will turn said sheave, for example the sheave 57, and the cylinder rigidly secured thereto to wind up the shutter door 95 on said cylinder to open the doorway and the operation of the other of said solenoids, for example the solenoid 22^a will turn said sheave and cylinder in the reverse direction to unwind the shutter door to close the 100 doorway.

In Figs. 1 and 2 the magnetic plungers, or cores, 19 and 20 are shown of a length substantially equal to the height of each door section, or more; also, it will be observed that the combined length of the aligned upper and lower solenoids is about equal to the height of the door-opening, or passage-way; and, also, that the magnetic plungers, when centered in either the upper solenoids or the lower solenoids, project somewhat into the other solenoids. In such a construction, the plungers will be responsive to either set of solenoids and will positively actuate the door sections the full distance of their movement. Furthermore, the plungers tend to seek equilibrium in the upper set or the lower set of solenoids, as the case may be, so that there is automatically exerted a slowing up or checking action near the end of the movement of the door-sections in either direction. The solenoids are fixedly secured to the wall or to the guides at the lateral edges of the door-opening in any desired manner. The improved mechanism requires little space 110 115 120 125 130

and can readily be applied to doors already installed, as is obvious.

While I have shown my invention in the particular embodiment above described, it will be understood that I do not limit myself to this exact construction as I may employ equivalents known to the art at the time of the filing of this application without departing from the scope of the appended claims.

10 What I claim is:

1. As a means for operating doors, the combination of a door movable in the plane of the door to open or close an opening, cables extending from the door, magnetic plungers connected with said cables, solenoids for actuating said plungers to open and close said door, electric circuits extending from said solenoids, two control switches in said circuits for actuating the door opening or door closing circuits as desired, interacting devices connected with said switches for preventing simultaneous closure of both said switches, said control switches being electromagnetically operated, operating circuits extending from the operating means of said switches, and operating switches in said operating circuits for selectively operating said control switches, whereby said operating switches may be located at a point remote from said door.

2. As a means for operating doors, the combination of a door movable in the plane of the door to open or close an opening, said door being movable vertically, cables extending from the door, magnetic plungers connected with said cables, solenoids for actuating said plungers to open and close said door, a counterweight substantially counterbalancing the weight of said door, electric circuits extending from said solenoids, two control switches in said circuits for actuating the door opening or door closing circuits as desired, and interacting devices connected with said switches for preventing simultaneous closure of both said switches.

3. As a means for operating doors, the combination of a door movable in the plane of the door to open or close an opening, said door being movable vertically, cables extending from the door, magnetic plungers connected with said cables, solenoids for actuating said plungers to open and close said door, a counterweight substantially counterbalancing the weight of said door, electric circuits extending from said solenoids, two control switches in said circuits for actuating the door opening or door closing circuits as desired, interacting devices connected with said switches for preventing simultaneous closure of both said switches, said control switches being electromagnetically operated, operating circuits extending from the operating means of said switches, and operating switches in said operating circuits for selectively operating said control

switches, whereby said operating switches may be located at a point remote from said door.

4. As a means for operating doors, the combination of a door movable in the plane of the door to open or close an opening, said door being movable vertically, a counterweight connected with said door substantially counterbalancing the weight of the same, two cables extending from said door, a magnetic plunger connected with each cable, two solenoids for actuating each plunger, whereby movement of said plungers in either direction by energization of the corresponding solenoids moves said plungers to positions to be actuated by the other solenoids associated therewith, electric circuits extending from said solenoids, two control switches in said circuits for actuating the door opening or door closing circuits as desired, and interacting devices connected with said switches for preventing simultaneous closure of both said switches.

5. As a means for operating doors, the combination of a door movable in the plane of the door to open or close an opening, said door being movable vertically, a counterweight connected with said door substantially counterbalancing the weight of the same, two cables extending from said door, a magnetic plunger connected with each cable, two solenoids for actuating each plunger, whereby movement of said plungers in either direction by energization of the corresponding solenoids moves said plungers to positions to be actuated by the other solenoids associated therewith, electric circuits extending from said solenoids, two control switches in said circuits for actuating the door opening or door closing circuits as desired, interacting devices connected with said switches for preventing simultaneous closure of both said switches, said control switches being electromagnetically operated, operating circuits extending from the operating means of said switches, and operating switches in said operating circuits for selectively operating said control switches, whereby said operating switches may be located at a point remote from said door.

6. As a means for operating doors, the combination of two door sections movable vertically in the plane of said sections away from each other to open the door and towards each other to close the door, cables connecting said sections to counterbalance the weight of one said section against the other, magnetic plungers connected with said cables, solenoids for actuating said plungers to move said sections in either direction as desired, electric circuits extending from said solenoids, two control switches in said circuits for actuating the door opening or door closing circuits as desired, in-

teracting devices connected with said switches for preventing simultaneous closure of both said switches, said control switches being electromagnetically operated, 5 operating circuits extending from the operating means of said switches, and operating switches in said operating circuits for selectively operating said control switches, whereby said operating switches may be located at a point remote from said door.

7. As a means for operating doors, the combination of two door sections movable vertically in the plane of said sections away from each other to open the door and 15 towards each other to close the door, cables connecting said sections to counterbalance the weight of one said section against the other, a magnetic plunger connected with each cable, two solenoids for actuating each 20 plunger, whereby movement of said plungers in either direction by energization of the corresponding solenoids moves said plungers to positions to be actuated by the other solenoids associated therewith, electric 25 circuits extending from said solenoids, two control switches in said circuits for actuating the door opening or door closing circuits as desired, interacting devices connected with said switches for preventing 30 simultaneous closure of both said switches, said control switches being electromagnetically operated, operating circuits extending from the operating means of said switches, and operating switches in said operating 35 circuits for selectively operating said control switches, whereby said operating switches may be located at a point remote from said door.

8. A means for closing and opening a 40 passageway through a wall, comprising the combination of two door sections disposed one above the other in vertical position adjacent said passageway, a first cable extending upwardly from each end of the upper 45 door section and secured thereto, a guiding sheave having a fixed support to receive each said first cable and direct it downwardly, a solenoid plunger connected with each downwardly extending first cable, a second 50 cable extending downwardly from each of said plungers and secured thereto, the lower end of each of said second cables being connected to one end of said lower door section, and solenoids around said cables and plungers to move said door sections away from 55 each other to open said passageways by actuation of certain of said solenoids and to move said door sections towards each other to close said passageway by actuation of others of said solenoids, whereby said door sections are connected in counterbalanced relation.

9. A means for closing and opening a passageway through a wall, comprising in combination, two door sections disposed one

above the other in vertical position adjacent said passageway, a guiding sheave journaled on a stationary support near each upper corner of said passageway, counterbalance connecting means connected with 70 each lateral edge of said upper door section and extending therefrom around the corresponding sheave and connected with the corresponding edge of the lower door section, a solenoid plunger forming part of one of 75 said connecting means, a first solenoid for moving said plunger in a direction to open said door sections, and a second solenoid for moving said plunger in a direction to close said door sections. 80

10. In means of the character set forth, the combination of a pair of oppositely moving door sections adapted to be connected in counterbalanced relation, flexible connections between said sections, including 85 magnetic plungers, sheaves about which said flexible connections pass, upper and lower solenoids coacting with said plungers, and electric circuits connected with said solenoids and equipped with circuit controlling 90 means enabling the lower solenoids to be energized to effect separation of the door sections and the upper solenoids to be energized to effect closure of the door sections. 95

11. In means of the character set forth, the combination of a pair of vertically movable door sections, flexible connections between said door sections, and supporting means therefor disposed and arranged to counterbalance the door sections with relation to each other and permit movements in opposite directions with respect to each other, said flexible connections including magnetic plungers, and solenoids coacting 100 with said plungers and adapted to reciprocate the same a distance corresponding with the distance of movement of the door sections. 105

12. In means of the character set forth, the combination of a pair of oppositely moving door sections adapted to vertical movement, counterbalance connections between said door sections and supporting means therefor, said counterbalance connections including magnetic cores, and solenoids 110 associated with said cores and equipped with electric circuits provided with circuit controlling means. 115

13. In means of the character set forth, the combination with a wall provided with a door opening, of a pair of oppositely moving door sections adapted to vertical movement, solenoids fixedly mounted at opposite sides of the door opening, flexible counterbalance connections between said door sections, including magnetic plungers adapted to operate through said solenoids, sheaves carried by said wall and supporting said flexible connections, and electric circuits connected with said solenoids and pro- 120 125 130

vided with circuit controlling means whereby the solenoids may be so energized as to open or close the door sections, at will.

14. In means of the character set forth, the combination with a wall provided with a door opening, of a pair of oppositely moving door sections adapted to vertical movement, solenoids fixedly mounted at opposite sides of the door opening, said solenoids extending substantially the length of the door opening and including upper solenoids adapted to move the door sections in one direction and lower solenoids adapted to move

the door sections in the other direction, flexible counterbalance connections between said door sections, including magnetic plungers adapted to operate through said solenoids, sheaves carried by said wall and supporting said flexible connections, and electric circuits connected with said solenoids and provided with circuit controlling means, whereby such solenoids may be so energized as to open and close the door sections, at will.

In witness whereof, I hereunto subscribe my name this 12th day of May, A. D. 1921.

MILLARD GILMORE.
